(57) **CLAIM**

The ornamental design for a display screen with animated user interface, as shown and described.

DESCRIPTION

FIG. 1 is the first image in a sequence for a display screen with animated user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof;

FIG. 11 is the eleventh image thereof;

FIG. 12 is the twelfth image thereof;

FIG. 13 is the thirteenth image thereof;

FIG. 14 is the fourteenth image thereof;

FIG. 15 is the fifteenth image thereof;

FIG. 16 is the sixteenth image thereof;

FIG. 17 is the seventeenth image thereof;

FIG. 18 is the eighteenth image thereof; and,

FIG. 19 is the nineteenth image thereof.

The broken line showings of content within the claimed design, the remainder of the user interface, and of the display screen illustrate unclaimed environment and form no part of the claimed design.

The subject matter of this patent includes a process or period in which an images changes into another image. This process or period forms no part of the claimed design.
